UNITED STATES PATENT OFFICE.

HUBERT ARNOLD, OF CALGARY, ALBERTA, CANADA.

KNIFE.

Application filed October 1, 1926, Serial No. 138,919, and in Canada December 23, 1925.

This invention relates to knives of the class having a detachable cutter, such as a razor blade, carried by a suitable holder.

One purpose of the invention is to provide 5 a knife of this class which is designed to permit placement or removal of the cutter to be easily effected without danger of injury to the hands of the user.

Another purpose of the invention is to 10 provide a holder having a cutter retaining latch which serves to positively position the cutter for convenient removal from the holder when said latch is moved to a cutter releasing position.

15 A further purpose of the invention is to provide a novel form of cutter guard cooperatively associated with the holder and cutter retaining latch and serving, in certain positions, to lock the cutter retaining latch 20 in operative position with respect to the cutter.

A still further purpose of the invention is to provide a knife of the class described which is constructed mainly of sheet metal 25 in such a manner as to permit economical quantity production.

Other purposes and advantages of the invention as well as the details of construction and combination of parts characterizing 30 the embodiment disclosed herein will be more readily understood from the following detailed description and accompanying drawings in which—

Figure 1 is a side elevation of the complete knife showing the cutter guard positioned to overlie substantially the whole length of the cutting edge.

Figure 2 is a view similar to Figure 1 with the cutter guard retracted to expose the cutting edge and with parts of the holder broken away to show interior structure.

Figure 3 is a view partly in side elevation and partly in section with the cutter guard removed and the cutter and cutter retaining latch in the positions which these parts occupy preliminary to securing the cutter in operative position.

Figure 4 is a vertical sectional view taken along line 4—4 of Figure 2.

50 Figure 5 is a vertical sectional view taken along line 5—5 of Figure 2.

Figure 6 is a vertical sectional view taken along line 6—6 of Figure 2 and

55 Figure 7 is a sectional view taken along line 7—7 of Figure 2.

Proceeding now to a detailed discussion

of the drawings, 5 designates a holder consisting of a pre-formed metal sheet folded to provide a rolled edge 6 and a pair of spaced side plates 7, the end portions of 60 which are secured together by bolts 8 and 9. These side plates are slotted transversely as indicated at 10 and the upper edge portions of one plate immediately adjoining the sides of the slot are turned downwardly 65 to provide an interrupted guide flange 11. In order to impart to the holder the requisite rigidity, a reinforcing rod 12 is secured in the folded edge 6 and is formed with a bent terminal 13 projecting laterally in the direction of the side plates and held in place by folding the terminal portions of one of the side plates therearound as indicated at 14.

Pivoted on the bolt 9 to operate 75 between the side plates 7 is a blade retaining latch consisting of a sheet of metal folded upon itself to provide a rolled edge 15 and a pair of side plates 16 which are pressed together to fit between the side plates 7 and are 80 apertured near one end to receive the pivot bolt 9 therethrough. Preferably the pivoted terminal of the latch is recessed as at 17 to give the clearance necessary for swinging the latch to and from the blade releasing position shown in Figure 3. Mounted for limited sliding movement in the rolled edge 15 is a rod 18 terminating at one end in a laterally projecting finger 19 having a curved end 20 adapted to function as hereinafter 85 described. A spring 21, encircling the rod 18, is confined between a collar 22 on the rod and one end wall of a slot 23 formed in the rolled edge 15 and serves to urge the rod 18 in one direction.

The cutter preferably consists of a razor blade 24 adapted to fit between side blades 7 of the holder as shown in Figures 1 to 3 and provided with terminal recesses 25 and 26. In positioning the blade within the holder the parts are first arranged as shown in Figure 3. In this figure the blade is shown in an angular position with one end fitted between the side plates 7 to engage the recess 25 with the bolt 8 which forms a pivot for the blade during subsequent movement of the latter to operative position. Movement of the blade from the position shown in Figure 3 to that shown in Figures 1 and 2 is accomplished by swinging the blade retaining latch inwardly toward the holder until the terminal 20 of the

finger 19 is engaged in the plate recess 26. Subsequent to this operation the inward movement of the retaining latch is continued and during this continued movement the blade 24, through the coaction of the recess 26 and the terminal 20 of the finger 19, is swung about the pivot point 8 to the position shown in Figures 1 and 2. It is desirable that the finger 19 be yieldingly pressed toward the blade during its engagement therewith and this is the function of the spring 21.

In order to provide for complete or partial coverage of the cutting edge I provide a cutter guard consisting of a U-shaped plate including a cylindrical portion 27 and spaced side members 28 and 29. In applying this guard the cylindrical portion 27 is slidably sleeved on the rolled edge 15 of the blade retaining latch with the side members 28 and 29 of the guard extending toward the holder. One of these side members, preferably that designated 28, has a portion of its lower edge extended and reversely folded to provide a guide flange 30 adapted, when the guard is positioned as shown in Figure 2, to slidably interlock with the aforesaid guide flange 11. When the guide flanges are interlocked as here described it will be noted that the blade retaining latch is secured in operative position. At a point remote from the inner end of guide flange 30 both of the side members 28 and 29 have their lower edges extended to form stops 31 and 32. When the cutter guard is moved to the position shown in Figure 1 the stop 31 is adapted to coact with the guide flange 11 as shown in Figure 1 and when the guard is retracted to the position shown in Figure 2, both of the stops 31 and 32 coact, in a similar manner with stops 33 carried by the side plates 7 of the holder.

Assuming the parts to be in the position shown in Figure 1 and that it is desired to use the cutter this is accomplished by sliding the cutter guard to the right until a sufficient portion of the cutting edge is exposed. In this respect it is to be noted that the guard will hold any position to which it is adjusted because of the frictional engagement obtaining between the guide flanges 11 and 30 and between the cylindrical portion 27 of the guard and the rolled edge 15. Inadvertent disengagement of the guard with the blade retaining latch during movement of the guard to blade covering or exposing positions is prevented by the stops hereinbefore referred to. When it is desired to remove the blade from the holder the parts are first arranged as shown in Figure 1 so as to disengage the guide flanges 11 and 30. With the parts in this position the cylindrical portion of the guard is grasped at about a point opposite the slots 10 and when an outward pull is exerted on the guard at this

point the blade retaining latch will swing outwardly to the position shown in Figure 3. During the initial outward movement of the retaining latch the curved end 20 of the finger 19 serves to pull the engaging end of the blade outwardly until the blade reaches the position shown in Figure 3 thereby facilitating removal of the blade without danger of cutting the hands of the user.

Whenever necessary the guard may be entirely removed from the blade retaining latch by sliding movement of the guard toward the free end of said latch.

Having fully described in the foregoing what I now conceive to be the preferred embodiment of my invention it will be understood that various changes in the construction and combination of elements may be resorted to within the scope of the invention as defined by the appended claims.

I claim:

1. A knife of the character described comprising a holder, a cutter mounted in the holder, a cutter retaining latch movably carried by the holder and directly engaging the cutter to retain the latter in operative position, said part serving, when the latch is moved to a cutter releasing position, to partially eject the cutter from the holder in order to facilitate complete removal of the cutter without injury to the hands of the user.

2. A knife of the class described comprising a holder, a detachable cutter mounted therein, means for securing the cutter to the holder including a pivotally mounted latch engageable with the cutter and a cutter guard slidably carried by said latch and operable thereon to cover or uncover the cutting edge of the cutter.

3. A knife of the class described comprising a holder, a detachable cutter mounted therein, a member passing through the holder and engaging in a recess formed in one end of the cutter and a latch having one end pivotally secured to the holder and the other end provided with a portion adapted to engage in a recess in the other end of the cutter to cooperate with said member in securing the cutter in operative position, said latch being movable relatively to the holder in a cutter releasing direction and the cutter engaging portion of the latch serving, during such movement of the latch, to cause the cutter to pivot about the member passing through the holder and to be thereby partially ejected from the holder.

4. A knife of the character described comprising a holder, a detachable cutter mounted therein, means for securing the cutter to the holder including a pivotally mounted latch engageable with the cutter and a cutter guard slidably carried by said latch and operable thereon to cover or uncover the cutting edge of the blade, said cutter guard

and holder being formed for interlocking engagement to secure the latch in operative position.

5. A knife of the class described comprising a holder having a transversely extending member at one end, a detachable cutter blade adapted to be inserted in the holder and provided with terminal recesses one of which is adapted to engage said member, 5 a latch pivoted at one end of the holder and provided at the other end with a member engageable in the terminal recess of the blade to secure the latter in the holder when the

latch is in operative position, a cutter guard slidably carried by said latch and movable thereon to cover and uncover the cutting edge of the blade when the latch is disposed in a blade retaining position, said cutter guard and holder being provided with interlocking flanges adapted to be engaged 15 and disengaged by moving the cutter guard to predetermined positions.

In testimony whereof I hereunto affix my signature.

HUBERT ARNOLD.
